UNITED STATES PATENT OFFICE.

DONALD B. FERGUSON, OF AURORA, MINNESOTA.

SOUNDING DEVICE.

1,055,153.

Specification of Letters Patent.

Patented Mar. 4, 1913.

Application filed March 6, 1911. Serial No. 612,694.

To all whom it may concern:

Be it known that I, DONALD B. FERGUSON, a citizen of the United States; residing at Aurora, in the county of St. Louis and 5 State of Minnesota, have invented certain new and useful Improvements in Sounding Devices, of which the following is a specification, reference being had therein to the accompanying drawing.

10 My invention relates to improvements in sounding devices used in navigation.

The object of my invention is to provide a device of this character which will by contact with the bottom of the river or body of 15 water cause a signal or alarm to operate to indicate that the same is on the bottom, thus not depending upon the sense of feeling as is the case with sounding devices now in use.

20 Another object of my invention is to provide an electric sounding device, whereby any considerable motion imparted to the same will be signaled to show that it has struck some obstruction, or the bottom, the 25 distance having no effect upon the sounding device.

A still further object of my invention is to provide a more simple, cheap and effective sounding device having certain details 30 of structure hereinafter more fully pointed out.

In the accompanying drawings—Figure 1 is a vertical sectional view of my improved sounding device coupled to an electric bell. 35 Fig. 2 is a view showing the device used as a sounding device for boats.

Referring now to the drawings, 1 represents the main body portion of my improved sounder and is provided with the upper 40 section 2, screwed within the body-portion and the lower weighted section 3, also screwed into the body portion and forming water-tight joints between the same. The body portion is formed with the chamber 4 45 therein, in which is arranged the metal bell-shaped casing 5, spaced from the body portion 1 by suitable rubber gaskets or rings 6 electrically insulating the same from the body-portion and also from the point 3 50 and the divisional plate 7 of the body-portion, and said bell-shaped casing is firmly held in the body-portion by the point 3 when the same is screwed into the said body-portion. The divisional wall or plate 7 is 55 formed within the body 1 just above the

upper end of the casing 5 through which extends a small rod 8 to the lower end of which is attached the tongue or clapper 9 suspended within the casing 5, but which does not normally engage or electrically 60 contact the casing in any way. This rod 8 in passing through the division wall 7 is made water-tight by means of a suitable stuffing gland 8'. An insulated wire 10 also passes through the division wall 7 and 65 is preferably made tight therethrough by means of a suitable stuffing gland 10', the lower end of the wire being connected to the side wall of the casing 5, as at 11. A second insulated wire 12 is connected to the 70 upper end of the rod 8 and it, together with the wire 10 extends upwardly, the two wires being united and forming the core of a suitable cable 13 which extends through the cap 2 and within the chamber 14 formed between the division 7 and the recessed cap 2. 75

Within the chamber 14 and attached to the division wall 7, are suitable eye-bolts 15 to which the outer strands 16 of the cable 13 may be attached for the purpose of suspending the plumb and insuring no strain coming upon the wire connections above described. The joint between the cable and the cap 2 is made water-tight by means of a suitable stuffing gland 17 which may be 80 made in a large measure to act as the gripping means in binding the cable 13 to the plumb in addition to fastening the outer strands 16 above described.

As is evident, the cable 13 may be any 90 desired length and the electric wires carried to any desired location and the latter are connected to a suitable battery 18 and bell 19 forming a complete electric circuit broken normally only within the casing 5, as one 95 wire terminates in the clapper 9 and the other in the casing 5. Thus it is seen that at any time when the plumb is thrown considerably out of plumb by any action whatsoever, the tongue or clapper 9 will engage 100 the inner wall of the casing 5 and thus close the electric circuit and cause the bell to ring or operate whatever signaling device is made use of. When used as a sounding device, contact with the bottom will cause the 105 plumb to tip and the signal be given as above described, which at once is seen to be a great convenience, as it is an exceedingly hard matter to detect the bottom when using a long line with a common sounder. 110

It is evident that there are many other uses to which the device may be put, such as the registering or recording of objects passing it and in turn causing the plumb to tip slightly and many alterations in the details of construction may be resorted to without departing from the spirit of my invention.

Having thus described my invention, what I claim and desire to secure by Letters Patent is:

1. A device of the character described, comprising a receptacle having an open lower end, a conducting casing within the receptacle and insulated therefrom, a plug screwed in the open lower end of the receptacle and holding the casing therein and insulated therefrom, a member pivoted within the casing and insulated therefrom, and an electric circuit having one wire connected to the casing and the other wire connected to the pivoted member whereby the circuit is closed when the receptacle is tilted to cause the pivoted member to contact with the casing.
2. A device of the character described, comprising a receptacle having a partition intermediate its ends, a plug screwed within the upper end of the receptacle and carrying the combined supporting and electric cable, a clapper pivoted in the partition, a conducting casing in the lower end of the receptacle surrounding the clapper and insulated from the receptacle, a plug screwed in the lower end of the receptacle and holding the casing therein and insulated therefrom, and an electrical circuit having the wires connected to the clapper and casing substantially as shown.
3. A device of the character described, comprising a receptacle having a partition intermediate its ends, a cap screwed into the upper end of the receptacle, a cable passing through the cap, a packing gland locking the cable to the cap, eyes carried by the partition and to which the winding of the cable is attached, a clapper pivoted in the partition, a conducting casing in the lower end of the receptacle surrounding the clapper and having insulating packing rings spacing it from the receptacle, a plug screwed into the receptacle and engaging an insulating ring and holding the casing therein, an electric insulated wire of a circuit passing through the partition and secured to the casing, a second insulated wire connected to the clapper connection, said

wires passing through the cable, and an indicator in circuit with said wires.

4. A device of the character described, comprising a plummet having a sealed chamber within its body, a circuit closer within said chamber comprising a movable member suspended from the top of said chamber and terminating at its free lower end above the bottom of the latter and a fixed member comprising an inner casing surrounding said movable member and of substantially the same dimensions as said chamber and insulated from the walls thereof, said movable member extending downwardly into the fixed member through the top thereof and terminal connections from said circuit closer to the exterior of said plummet.

5. A device of the class described comprising a body provided with a chamber open at one end, means closing such open end, a fixed member of a circuit closer held in the chamber solely by said means and insulated from the chamber, a movable circuit closer member extending into the chamber in co-operative relation to said fixed member, and circuit wires connected with the said members.

6. A device of the class described comprising a body provided with a chamber open at one end, a hollow metallic member disposed in and insulated from the walls of the chamber, means closing the end of the chamber and holding the said member therein, a movable member extending into the chamber and into the said hollow member to form therewith a circuit closer, and circuit wires connected with the said members.

7. A device of the class described comprising a body provided with a chamber and made in two sections rendering the chamber accessible, a hollow metallic member in the chamber, insulating elements surrounding the said member, insulating elements clamped between the ends of said member and walls of the chamber by the securing of the sections together, a movable member extending into the chamber and into the said fixed member to form with the latter a circuit closer, and circuit wires connected with the said members.

In testimony whereof I hereunto affix my signature in the presence of two witnesses.

DONALD B. FERGUSON.
